FLAT KNITTING MACHINE

Max Nebel, Chemnitz, Germany; vested in the
Alien Property CustodianApplication November 13, 1941, Serial No. 418,869
In Germany August 10, 1937

10 Claims. (Cl. 66—91)

This invention which constitutes a continuation in part of my co-pending application Ser. No. 241,255, filed November 18, 1938, relates to a flat knitting machine for knitting plush fabric and more particularly to that type of machine having a bed of united spring beard needles and sinkers movable at right angles thereto for the purpose of sinking loops about the shanks of the needles, the sinkers being provided with vertically spaced throats open in front. Two separate threads are fed, one to the lower throat and the other to the upper throat which is termed the plush throat and which sinks longer loops about the needle shanks than does the lower throat. These longer loops are termed plush loops.

The machine is provided with two types of sinkers; jack sinkers which are advanced seriatim to sink the threads about the needle shanks as the yarn is fed thereto, and dividing sinkers which alternate with said jack sinkers and which are advanced en masse to divide the thread previously sunk by the jack sinkers equally among the needles. In the prior art machines it was common to use horizontal separator members which were moved between the plush thread and ground thread to hold the two threads vertically separated during formation of the loops.

It is the object of my invention to avoid the use of said separators by modifying the needle and sinker movement.

One modification for accomplishing this result is shown in the accompanying drawing and described below. In the drawings:

Figure 1 is a sectional side elevation of the flat knitting machine according to the invention;

Fig. 1a is a sectional detail view of the mechanism for controlling the vertical motion of the needle bar;

Fig. 1b is a sectional detail view of the mechanism for controlling the horizontal motion of the needle bar;

Fig. 1c is a sectional detail view of the mechanism for controlling the forward and return motion of the facing bar;

Fig. 1d is a sectional detail view of the mechanism for controlling the motion of the knocking-over comb;

Fig. 2, a top view of the position of the ground thread and plush thread guides during the sinking operation;

Fig. 3, a front view of the position of the ground thread and plush thread guides during the sinking operation;

Figs. 4 to 7 show the loop forming tools on an

enlarged scale in four different essential positions seen from the side; and

Fig. 8 is a front view of the positions of several sinkers and needles as shown in Fig. 5.

5 The plush thread guides 31, 32 and the ground thread guides 33, 34 are so arranged that the guides 31, 32 deliver their plush thread just below the upper edge of the jack sinkers 35 and the guides 33, 34 their ground thread barely above the upper edge of the dividing sinkers 36. The arrangement of the thread guides and their drive are well known and need not be described in detail. The arrangement is shown in Fig. 1 which indicates in profile the set of four thread guides 10 31, 32, 33, 34 disposed on rails 51, 52, 53, 54 in a guide 55. Displacement of the carriage 56 causes those thread guides that are to operate to be driven so that they properly place their thread in front of the sinkers.

15 In Figs. 2 to 8 it is assumed that the thread guides 31 and 33 are laying threads, the guide 31 positioning the plush thread 3 and the guide 33 the ground thread 4. The other two thread guides 32, 34 are not visible in the figures, since 20 they are assumed not to deliver thread and for this reason remain at the edge, as they are not passed over the row of sinkers.

25 The jack sinkers 35 possess two throats 35b and 35a which lies above and in front of the throat 35b. The throat 35a has a vertical or only slightly forwardly inclined lower edge. The upper throat 35a is the plush throat and the lower throat 35b the ground thread throat.

The dividing sinkers 36 are fitted with only 30 one ground thread throat 36b, and their upper edge 36c is located just below the plush throat 35a of the jack sinkers.

Both sinkers are disposed in known manner in slots of the sinker head 37 in such manner 35 that they can be moved to and fro.

The jack sinkers 35 receive their sinking motion through the medium of the jacks 51 movably disposed about the member 82. The swinging motion of the jacks 51 is brought about by 40 a curve of the slur 58 arranged in a carriage 56 in which it is moved to and fro on the path 60.

Owing to the displacement of the slur 58 in the longitudinal direction of the machine the jacks 51 are successively moved against the rear edge 45 of the jack sinkers 35 and advance these sinkers one after the other. This is well known, so that it will not be necessary to show and describe the manner of producing this to and fro motion of the slur 58.

The dividing sinkers 36 act only after all jack

sinkers have been advanced, i. e., when the entire row of jack sinker loops has been sunk, and are advanced all at once. For this purpose, the bar 61 of the facing bar 61a, by abutting against the upwardly directed projection 36g of the dividing sinkers 36, pushes all dividing sinkers 36 in front of it. The jack sinkers 35 also have an upwardly directed projection 35g which, however, is not as long as the projection 36g of the dividing sinkers 36, so that at the advance of the facing bar 61a jack sinkers 35 cannot be engaged.

The jack sinkers 35 and the dividing sinkers 36 are jointly withdrawn, which is also effected by the facing bar 61a which possesses in front a downwardly directed edge 61b. If, the sinkers are to be drawn back, the facing bar 61a is lowered to such an extent that its front edge 61b engages the front edges of the upwardly directed projections 35g and 36g of the sinkers, whereupon the facing bar 61a moves back again, so that all sinkers are carried along. This manner of moving the dividing sinkers and of withdrawing all sinkers is known also.

The facing bar 61a is lowered in exactly the same way as in prior art machines, but the forward motion of the dividing sinkers and the withdrawal motion of all sinkers are modified in my machine. Forward and return motion is imparted to the facing bar by a two-armed lever 90 disposed on a shaft 91 (Fig. 1c). The upper arm of the lever 90 is articulated to the rearwardly extending arm 61c of the facing bar 61a, and the lower arm thereof is provided with a roll 92 which abuts against a disc cam 93 secured to an eccentric shaft 94. The to and fro motion of the facing bar 61a as well as its stoppage are controlled by the rotation and shape of the cam 93.

The frame needles 39 are held in the bar 95 in known manner. The bar 95 is flexibly supported by an arm 73a of several double-armed levers which are secured to a shaft 72 and whose other arm 73 abuts by means of a roll 96 against a disc cam 71. This arrangement is known of course. The shape of the cam 71 is normal, and the needle bar 95 and therefore the frame needles 39 perform the normal up and down motion (Fig. 1a). The frame needles 39 carry out, however, also a horizontal forward and return motion (Fig. 1b) which is made possible by the flexible connection of the bar 95 at 78 with the lever arm 73a and the attachment of a lever arm 77 to the bar. To this lever arm 77 a lever 76 is articulated which is hung on the pin 97 of the lever 75 secured to a shaft 74 and, by means of the roll 98 rotatably disposed at the lower end thereof, subjected to the action of a disc cam 79 which like the disc cams 93 and 71 is attached to the eccentric shaft 94. The disc cam 79 has a shape differing from that of the known cams, since in the machine according to the invention the horizontal motion of the frame needles toward and from the presser members is eliminated, and only the other horizontal motions of the frame needles 39 remain.

The flat knitting machine according to the invention is not equipped with a press of known type which is firmly arranged on the sinker head, but possesses a presser comb 99 positioned in front of the sinker head 37 and fitted with presser teeth 38. The presser comb 99 is secured to the knocking over comb bar 100 which supports the knocking over sinkers 40, and the teeth 38 of the presser comb 99 extend between

the sinkers 40. The presser comb 99, together with the knocking over comb, carries out a horizontal forward and return motion which replaces the omitted horizontal pressing motion of the needles. This pressing motion of the comb 99 and of the knocking over sinkers 40 is produced as follows:

The knocking over comb bar 100 has downwardly extending arms 102 to the lower end of 10 which a link 103 is attached which is connected to a double-armed lever 104 whose lower arm is provided with a link 105 connected with a single lever 106. The double-armed lever 104 is placed on a shaft 107 and the single lever 106 15 on a shaft 72 (Fig. 1d). The single lever 106 is provided at its lower end with a roll 108 which is subjected to the action of a disc cam 109 secured to the eccentric shaft 94.

The cam 109 is so shaped that the presser 20 teeth 38, according to the invention, carry out individual forward and return motions with respect to the needles and close the beards of the frame needles, so that the old loops on the frame needles may be cast off as meshes over 25 the newly formed loops. This relative pressing motion between the frame needles and the presser edges is known, but according to the invention this pressing motion is performed not by the frame needles but by presser tools having the form of presser comb 99 fitted with teeth 38. The fact that the knocking over sinkers 40 cooperate in the motion of the presser comb 99 has no influence upon the mode of operation of the machine.

35 The operation of the machine will now be described. By moving along the row of sinkers the thread guides 31, 33 place their plush thread 1 and their ground thread 3 before the plush throat 35a and the ground thread throat 35b of the jack 40 sinkers and while doing so are somewhat in advance of the successively advancing jack sinkers 35, or, in other words, each thread guide has passed already a jack sinker before the latter begins to advance for sinking. The advance of the 45 ground thread guide 33 is normal but that of the plush thread guide 31 shorter than usual, as indicated in Figs. 2 and 3 which illustrate the position of the thread guides and of the threads after a number of loops has been sunk.

50 Fig. 4 shows the position of the tools after all loops have been sunk seen from the side whilst Figs. 2 and 3 show this position, respectively, from above and the front. The advance motion of the jack sinkers for sinking purposes is normal, and the slur carriage 58 effecting this motion does not differ in the tempo of its to and fro motion along the rail from that prevailing in prior art machines.

According to Fig. 4, the advance of the dividing sinkers 36 has begun already, as usual, so as 60 to enable the point 36d positioned above the dividing sinker and the ground thread throat 36b to enter below the groove 38a between the frame needles 39. When the nose 36d is located between the needles, the sinkers remain in a position at which the throat 36b cannot act as yet upon the ground thread. The actual dividing motion when the ground thread throat 36b begins to push the ground thread between and 65 through the frame needles to form loops occurs later than usual, i. e., when, as indicated in Fig. 70 5, the frame needles 39 have descended to such an extent that the plush thread 3 sunk already to form plush loops 41 is positioned in the hook 75 of the frame needles 39.

Fig. 5 shows the actual beginning of the dividing operation, i. e., the moment when the throat 36b of the dividing sinker begins to act upon the thread 1 which has previously been sunk by the jack sinkers in their ground thread throat 35b to form loops 42. The frame needles 39 carry out the normal downward motion, and the cam 71 bringing about this motion is of regular shape. During this period the presser teeth 38 stand back so as not to interfere with the needles 39. The disc cam 109 controlling the motion of the teeth 38 rolls with its circular portion over the rolls 108, so that the lever mechanism 106, 105, 104, 103, 102 transmitting the motion and thus also the knocking over comb bar 103 and the presser comb 99 stand still in their extreme rearward position, as indicated in Figs. 4 and 5.

Fig. 6 shows the completion of the dividing operation for the ground thread. At this time the presser teeth 38, owing to corresponding elevations of the disc cam 109, have moved up to the still farther descending frame needles 39 and closed the needle hook in consequence whereof the old meshes 110 on the top edge of the knocking over combs 40, during farther downward motion of the frame needles 39, can be cast off from the frame needles over the hook and the newly formed loops.

While the ground thread 1 is divided to form loops 42 the dividing sinkers 36 have not acted upon the plush thread 3 which still is sunk only to form loops 41 and hangs between the needle hook and the throat 35a of the jack sinker. As during dividing of the ground thread 1 the jack sinkers 35 are somewhat drawn back for the reason that the divided loops 42 are made shorter than the sunk loops 41, the sunk plush thread loops 41 suspended between the needle hook and the throat 35a are of course loosened. In order to make sure that the plush thread is placed in the hook in spite of this loosening and to prevent it from being pierced by the point of the hook or even remaining outside the latter and dropping from the needle, the dividing operation as stated and shown in Fig. 5 begins only when the needle is so far down that the plush thread is in the hook. This loosening of the sunk plush thread loops 41 is indicated by the wavy appearance of the loop 41 in Fig. 6.

During the pressing operation shown in Fig. 6 the frame needles 39 move farther downwardly at ordinary speed and divide the plush thread 3, sunk into loops 41, on the upper edge 36c of the dividing sinker to form loops 41a. The sunk loops 41 are thereby made shorter and slide downwardly out of the throat 35a, for which purpose the lower edge of the throat 35a extends in vertical direction or is only slightly forwardly inclined. During the farther descent of the frame needles and the dividing of the loops 42 the old meshes 110 are landed on the closed needle hook and the presser teeth 38, due to a corresponding shape of the disc cam 109, move again from the needle and back into their initial position as shown in Figs. 4 and 5. This position of the sinkers and frame needles after completion of the dividing of the plush thread 3 is shown in Fig. 8 as seen from the front.

Only after these operations, and later than usual, begins the joint return motion of the dividing and jack sinkers by withdrawing the downwardly moved facing bar 61a. This delayed beginning of the return motion of the facing bar 61a is due to a corresponding shape of the disc

10 arm 93 which with the aid of the roll 92 and levers 90 and 61c produces the horizontal motion of the bar 61a. The retarded withdrawal of the jack and dividing sinkers is possible, because the frame needles do not perform a horizontal motion during the pressing operation and therefore also not during dividing of the plush thread 3 in downward direction, so that the normal or earlier beginning of the return motion of the sinkers is not necessary. This return motion begins only after the plush thread 3 has been divided and the simultaneously occurring pressing operation is completed. Owing to this return motion the sinkers withdraw from the sunk and divided loops and release them for casting off.

I claim:

1. In a flat knitting machine, a needle bar, frame needles firmly arranged in said bar, thread guides for supplying ground thread and plush 20 thread to the needles, jack sinkers having a throat for the ground thread and, above and in front thereof, a throat for the plush thread for sinking the plush thread and forming loops 25 therefrom that are longer than the ordinary loops from the ground thread, dividing sinkers whose upper edge lies below the throat of the jack sinkers and each of which has a throat for the ground thread for dividing the ground thread in forward direction and a nib located above said 30 throat for the ground thread, presser tools that are horizontally movable to and fro and means for moving said parts, said thread guide for the ground thread terminating just above the upper edge of the dividing sinkers and said guide for 35 supplying plush thread terminating just below the upper edge of the jack sinkers, said ground thread guide moving toward the sinker concerned with normal lead and said plush thread guide with less lead, said needle bar moving without horizontal pressing motion but otherwise performing its normal motion, particularly in upward and downward direction, said jack sinkers carrying out the normal forward motion for the 40 sinking operation, said dividing sinkers retarding 45 the dividing operation and beginning with it only when the plush thread is engaged by the needle hooks which thread, by the downward motion of said needle bar, is divided by the needles on the upper edge of the dividing sinkers while said 50 presser tools horizontally move up to the needles and close the hooks thereof, whereupon after completion of the pressing operation and of the downward dividing of the plush thread the return motion of the jack and dividing sinkers begins 55 and the loops formed from the ground and plush threads are released for the knocking over operation.

2. Flat knitting machine according to claim 1, in which the dividing sinkers are advanced between the frame needles so that the nibs above their ground thread throats enter between the needle shanks below the needle grooves and the dividing sinkers are pushed with their points between the needles only to such an extent that dividing of the ground thread does not begin as yet, and means for producing this motion.

3. Flat knitting machine according to claim 1, in which the dividing sinkers are advanced between the frame needles so that the nibs above their ground thread throat enter between the needle shanks below the needle grooves and the dividing sinkers are pushed with their points between the needles only to such an extent that dividing of the ground thread does

not begin as yet, and means for producing the motion of the needle bar, facing bar and presser comb, said means including rotary disc cams connected by levers with said parts and shaped so that at each phase of the mesh-forming process the frame needles, the jack and dividing sinkers and the presser teeth are moved in timed relation.

4. In a flat knitting machine, a needle bar, frame needles in the bar, a thread guide for supplying ground thread, and another thread guide for supplying plus thread, to the needles, jack sinkers having a throat for the ground thread and, above and in front thereof, a throat for the plush thread for sinking the ground thread and the plush thread in forward direction and forming loops from the latter that are longer than the loops from the ground thread, dividing sinkers whose upper edge lies below the plush throat of the jack sinkers and which engages the ground thread only, said dividing sinkers having each a throat for the ground thread and a nib located above said throat for dividing the ground thread, said thread guide for supplying ground thread terminating just above the upper edge of the dividing sinkers and said guide for supplying plush thread terminating just below the upper edge of the jack sinkers, means for moving the needle bar with respect to the dividing sinkers so that said nib passes between and through the plush and ground threads sunk at different levels, means for obviating the necessity of a horizontal motion of the needle bar relative to the press, said driving sinkers beginning later than usual with the distribution of the ground thread loops so that the plush thread loop is engaged by the hook of each needle at the moment the ground thread loops are divided, and means for moving the needle bar with respect to the dividing sinkers so that the plush thread is divided in downward direction only.

5. In a flat knitting machine, a needle bar, frame needles in the bar, a thread guide for supplying ground thread, and another thread guide for supplying plush thread, to the needles, jack sinkers having a throat for the ground thread, and, above and in front thereof, a throat for the plush thread for sinking the ground thread and the plush thread in forward direction and forming loops from the latter that are longer than the loops from the ground thread, dividing sinkers whose upper edge lies below the plush throat of the jack sinkers and which engages the ground thread only, said dividing sinkers having each a throat for the ground thread and a nib located above said throat for dividing the ground thread, said thread guide for supplying ground thread terminating just above the upper edge of the dividing sinkers and said guide for supplying plush thread terminating just below the upper edge of the jack sinkers, means for moving the needle bar with respect to the dividing sinkers so that the point of said nib enters the needle row below the needle groove, means for moving the needle bar with respect to the dividing sinkers so that said nib passes between and through the plush and ground threads sunk at different levels, means for obviating the necessity of a horizontal motion of the needle bar relative to the press, said dividing sinkers beginning later than usual with the distribution of the ground thread loops so that the plush thread loop is engaged by the hook of each

idle at the moment the ground thread loops are divided, and means for moving the needle bar with respect to the dividing sinkers so that the plush thread is divided in downward direction only by the downward movement of the needles.

6. In a flat knitting machine according to claim 5 wherein the return motion of the sinkers after completion of the dividing operation begins only when the pressing operation is completed and the putting-on operation is initiated.

7. In a flat knitting machine, a needle bar, frame needles in the bar, a thread guide for supplying ground thread, and another thread guide for supplying plush thread, to the needles, jack sinkers having each a throat for the ground thread and, above and in front thereof, a throat for the plush thread for sinking the ground and plush threads in forward direction and forming loops from the plush thread that are longer than the loops from the ground thread, dividing sinkers whose upper edge lies below the plush throat of the jack sinkers and which engages the ground thread only, said dividing sinkers having each a throat for the ground thread and a nib located above said throat for dividing the ground thread, said thread guide for supplying ground thread terminating just above the upper edge of the dividing sinkers and said guide for supplying plush thread terminating just below the upper edge of the jack sinkers, means for moving the needle bar with respect to the dividing sinkers so that said nib passes between and through the plush and ground threads sunk at different levels, means for obviating the necessity of a horizontal motion of the needle bar relative to the press, said dividing sinkers beginning later than usual with the distribution of the ground thread loops so that the plush thread loop is engaged by the hook of each needle at the moment the ground thread loops are divided, said press carrying out a horizontal to and fro motion.

8. In a flat knitting machine, a needle bar, frame needles in the bar, a thread guide for supplying ground thread, and another thread guide for supplying plush thread, to the needles, jack sinkers having each a throat for the ground thread and, above and in front thereof, a throat for the plush thread for sinking the ground thread and the plush thread in forward direction and forming loops from the latter that are longer than the loops from the ground thread, dividing sinkers whose upper edge lies below the plush throat of the jack sinkers and which engages the ground thread only, said dividing sinkers having each a throat for the ground thread and a nib located above said throat for dividing the ground thread, said thread guide for supplying ground thread terminating just above the upper edge of the dividing sinkers and said guide for supplying plush thread terminating just below the upper edge of the jack sinkers, means for moving the needle bar with respect to the dividing sinkers so that the point of said nib enters the needle row below the needle groove, means for moving the needle bar with respect to the dividing sinkers so that said nib passes between and through the plush and ground threads sunk at different levels, means for obviating the necessity of horizontal motion of the needle bar relative to the press, said dividing sinkers beginning later than usual with the distribution of the ground thread loops so that the plush thread loop is engaged by the hook of each needle at the moment the ground thread loops

are divided, means for moving the needle bar with respect to the dividing sinkers so that the plush thread is divided in downward direction only, and means for causing the press to carry out a horizontal to and fro pressing motion.

9. In a flat knitting machine, a needle bar, frame needles in the bar, a thread guide for supplying ground thread, and another thread guide for supplying plush thread, to the needles, a jack sinker for each needle, with a throat for the ground thread, a throat for the plush thread, a forwardly inclined edge extending downwardly from the throat for the plush thread, the two throats being so positioned with respect to each other that longer loops are sunk from the plush thread than from the ground thread, a dividing sinker for cooperation with each jack sinker, which dividing sinker has a throat for the ground thread, a dividing edge on the dividing sinker which is at a level not higher than the lower end of the substantially vertical edge, said needle bar being adapted for up and down movements in time with the sinking and dividing movements of the sinkers without causing it to carry out a horizontal to and fro presser motion. 25

10. In a flat knitting machine, a needle bar, frame needles in the bar, a thread guide for supplying ground thread, and another thread guide for supplying plush thread, to the needles, a jack sinker for each needle, with a throat for the ground thread, a throat for the plush thread, a forwardly inclined edge extending downwardly from the throat for the plush thread, the two throats being so positioned with respect to each other that longer loops are sunk from the plush thread than from the ground thread, a dividing sinker for cooperation with each jack sinker, which dividing sinker has a throat for the ground thread, a dividing edge on the dividing sinker which is at a level not higher than the lower end of the substantially vertical edge, said needle bar being adapted for up and down movement in time with the sinking and dividing movements of the sinkers without causing it to carry out a horizontal to and fro presser motion, and a press movable horizontally to and fro for each stage of the pressing operation in time with the sinking and dividing movements of the sinkers and the movements of the needles. 15

MAX NEEBEL.
